UNITED STATES PATENT OFFICE.

LOREN W. RICKEY, OF SANTA CRUZ, CALIFORNIA, ASSIGNOR OF ONE-HALF TO WIL-
LIAM O. KERRICK, OF SANTA CRUZ, CALIFORNIA.

DRYING FRAME.

Application filed May 12, 1924. Serial No. 712,783.

To all whom it may concern:

Be it known that I, LOREN W. RICKEY, a citizen of the United States, and a resident of Santa Cruz, in the county of Santa Cruz and State of California, have invented certain new and useful Improvements in Drying Frames, of which the following is a specification.

It is one object of the invention to provide a frame for drying curtains true to shape and that will occupy but a small amount of space.

It is another object to provide a device of the character indicated that will permit the drying of one curtain while another is being arranged in position.

It is still another object to provide a device of the character indicated that will satisfactorily dry a curtain without permitting the same to sag.

It is also an object of the invention to provide a simple, economical, and highly efficient means for stretching the curtain on the frame, and to provide an efficient means for securing the curtain to the frame during the drying process.

In the drawing:

Figure 1 is an end elevation of the device as arranged in conjunction with a dryer.

Figure 2 is a face view of the drying frame.

Figure 3 is an enlarged section on line 3-3 of Figure 2.

Figure 4 is an enlarged section on line 4-4 of Figure 2.

Figure 5 is an enlarged section on line 5-5 of Figure 2.

Figure 6 is an enlarged plan view of the part "A" in Figure 2, parts broken away.

Figure 7 is an enlarged plan view of the part "B" in Figure 2, parts broken away.

Figure 8 is an enlarged detail of the gear shifting device.

Referring more particularly to the drawing the main body portion of the frame is made up of two channel iron frames 1-1 of uniform size and placed edge to edge as clearly shown in Figure 3, in which position they are fastened together with two sheets of sheet metal 2-2 and a sheet of asbestos 3 therebetween.

This construction makes a complete double frame, the two sides being insulated from each other so that the side pre-

sented to the heating medium, as steam coils 4^a in box 4, gets the full benefit of the heat while the outwardly directed side may be operated without discomfort to the operator.

This frame is provided with pivots 5-5, one at each end and arranged on its longer axis. On these pivots are arranged supporting rods 6-6 fitted with turnbuckles 7-7 for adjusting its height from the floor, the rods 6-6 being suspended from hooks as indicated at 8 so that the frame may be freely swung outward for reversing but normally hung parallel with the heating box 4.

Since the two sides of the device are exactly alike the following detailed description of one side will apply equally as well to the other.

At 9-9 are two carrier strips of sheet metal bent and formed longitudinally as shown in Figure 4 to hold a strip of material having a wire pile 10 and mounted on travellers 11. These travellers 11, one on each end of each strip 9, are mounted on threaded rods 12 supported on opposite sides of frame 1 by bearings 13, one pair of rods being threaded in an opposite direction to the other pair so that simultaneous rotation of all the rods in the same direction will move the strips 9-9 at a uniform rate of speed in opposite directions.

The rotation of rods 12 is accomplished by a shaft 14 extending across frame 1 midway its length and carrying bevel gears 15 meshing with the opposing gear 16 on each pair of rods 12. Rotation of shaft 14 by handle 17 will, therefore, advance or retract carrier strips 9 as desired.

At 18 are a pair of heavier carrier strips formed of channel irons having wire pile strips 18^a slidably mounted thereon by folded sheet metal strips 20 as shown in Figure 5. These strips are arranged longitudinally of frame 1 and at right angles to strips 9 and are mounted on rods 21 by means of travellers 22. These rods 21 are threaded in opposite directions at opposite ends and are mounted on opposite ends of frame 1 by means of bearings 23.

It is obvious that if these two rods are rotated at the same time the strips 18 will be moved toward or away from each other. To accomplish this action, two of the axially aligned rods 12 are hollow and form 110

bearings for rods 24 provided with gears 25 on their inner ends and gears 26 on their outer ends, the gears 26 meshing with gears 27 on rods 21.

5 The shaft 14 has a spindle 28 in the end thereof projecting between one set of opposing gears 16 and carrying a gear 29 adapted to mesh with opposing gears 25.

In bearing 30 for shaft 14 is a pin 31 engaging a double triangular slot 32 in shaft 14. When pin 31 engages the outer end of said slot the gears 15 engage gears 16 and strips 9—9 are simultaneously moved in opposite directions. If, however, the shaft 14 10 is pulled outwardly so that pin 31 engages the inner end of slot 32, the gears 15 are disengaged from gears 16 and gear 28 is thrown into engagement with the gears 25 so that revolving shaft 14 will move strips 18—18 15 simultaneously in opposite directions.

It may be seen from the foregoing that I have provided a device that occupies but a small amount of space, is quickly reversed for replacing the dried curtains with freshly 25 washed and wet ones, and permits quick, accurate and positive adjustment of the stretcher elements to the curtain to be dried. Furthermore, since the curtains are quickly dried in a vertical position they cannot sag 30 and therefore dry true to shape.

It is to be understood, of course, that while I have herein shown and described one specific embodiment of the invention, changes in form, construction and method 35 of operation may be made within the scope of the appended claims.

I claim:

1. A device of the character described comprising a stretcher frame, means for 40 mounting a curtain upon each side thereof, and a swinging support pivotally connected to said frame whereby to permit its reversal in said support.

2. A device of the character indicated 45 comprising a frame, means for stretching a curtain thereon, swinging supports pivotally connected to said frame at each end of its horizontal axis, and adjusting devices arranged in said supports.

50 3. A device of the character indicated comprising a frame, means for stretching a

curtain thereon, swinging supports pivotally connected to said frame at each end on its horizontal axis, a heater arranged parallel with an adjacent to said frame when suspended in a vertical plane, and guide means carried by said heater and adapted to engage said frame when being rotated on said pivotal connections.

4. A device of the character indicated 60 comprising a frame, a pair of oppositely threaded and axially aligned rods revolvably mounted adjacent to each side thereof, a traveller threaded on to each rod, a curtain supporting bar mounted upon each pair of similarly moving travellers, a pair of curtain supporting bars mounted on said frame to move at right angles to said first mentioned bars, and means for simultaneously moving either pair of bars in opposite directions.

5. A device of the character described comprising a stretcher frame, means for mounting a curtain upon each side thereof a vertically arranged heater, brackets arranged over said heater, and supporting arms pivotally connected to said frame and swingingly connected to said brackets whereby to normally suspend said frame in parallel relation to and adjacent to said heater 70 and permit its reversal relative thereto.

6. A device of the character described comprising a revoluble stretcher frame, means for mounting a curtain upon each side thereof, a vertically arranged heater, 75 and supports for said frame normally supporting said frame in parallel relation to and in close proximity to said heater but movable relative thereto whereby to permit rotation of said frame.

7. A device of the character described comprising a revoluble stretcher frame, means for mounting a curtain upon each side thereof, a heat insulating partition inserted between said curtain mounting means, 95 a vertically positioned heater, and a support for said frame normally supporting the same in parallel relation to and in close proximity to said heater but movable relative thereto whereby to permit rotation of 100 said frame.

LOREN W. RICKY.
